[57] CLAIM

The ornamental design for an ice skate blade sharpener, as shown and described.

DESCRIPTION

FIG. 1 is a perspective view of the ice skate blade sharpener of my new design;

FIG. 2 is a top plan view thereof;

FIG. 3 is a bottom plan view thereof;

FIG. 4 is an end elevational view thereof, the opposite end being a mirror image thereof;

FIG. 5 is a side elevational view thereof, the opposite side being a mirror image thereof; and,

FIG. 6 is a sectional view taken along the line 6—6 of FIG. 5.
